UNITED STATES PATENT OFFICE.

RUFUS M. STONE, OF OKLAHOMA CITY, OKLAHOMA.

BURNER.

Application filed January 27, 1926. Serial No. 84,212.

My present invention has reference to a hydro-carbon burner, and particularly to a means for vaporizing the oil and to cause a mixing of air with such vapor to obtain a 5 perfect combustion of the fuel.

A further object is the provision of means whereby the incoming oil is subjected to intense heat to transform it into a gaseous condition prior to being ignited and to effect 10 economy in the consumption of fuel by mixing air so as to obtain an intense heat, and further wherein means is provided for regulating the varying intensities of the flame and heat from the burner.

15 To the attainment of the foregoing, the invention consists in the improvement as hereinafter described and definitely claimed.

In the drawings:

Figure 1 is a top plan view of a distillate 20 oil burner in accordance with my invention.

Figure 2 is a side elevation.

Figure 3 is a sectional view on the line 3—3 of Figure 1.

Figure 4 is a top plan view of the center 25 or dome member of the improvement.

Figure 5 is a bottom plan view of the outer or crown member of the improvement.

Figure 6 is a perspective view of the cross 30 bar employed.

The base 1 of my improved hydro-carbon burner has an outer continuous flange 2 and a lower continuous flange 3 which is disposed inwardly with respect to the outer flange 2. The flange 3 is designed to rest on a grate 35 of a stove in which the burner is arranged, and in this connection it may be well to state that the improvement is designed for both heating and cooking purposes.

The base 1 has a central rounded opening 40 4 therethrough that is surrounded by an upstanding flange 5. Resting on the base, inward of the flange 5, there are the spaced legs 6 formed on the outer face of an annular flange 7 of the intermediate or dome 45 member 8 of the improvement. The cross sectionally rounded top of the member 8 has its outer face, at points radiating from its center, formed with depressions 9 that provide oil conduits, and the said center of the member 8 has a threaded opening therethrough that is surrounded by an inner flange 10. Screwed through the mentioned opening there is an oil jet nipple 11. The nipple 11 has a restricted bore therethrough. 50 This nipple is screwed on one end of a T 12, the lower passage in the T being closed

by a threaded plug 13 and screwed on this plug there is a centrally threaded portion 14 of a cross bar 15. As shown in Figure 3 of the drawings, the cross bar has its ends 60 contacting with the outer or lower face of the base 1, and by an arrangement as above described it will be noted that the nipple is effectively sustained on the intermediate member 8 and that the dome member is likewise effectively sustained on the base. 65 Screwed in the lateral branch of the T-coupling 12 there is an oil conductor pipe 16. The outer end of this pipe rests on the flange 2 of the base and the said pipe is 70 designed to have screwed thereon a suitable coupling for a pipe which is connected with a supply of oil, and the passage through which pipe is, of course, valve controlled.

The oil jet nipple 11 is extended a suitable 75 distance above the top of the member 8, and the said member 8 has the flanged portion 7 thereof, on its upper or outer face, formed with equidistantly spaced preferably right-angledly arranged lugs 17. The outer or crown member of the improvement is indicated by the numeral 18, and is formed at its open end with an outstanding continuous flange 19, the said flange at equidistantly spaced intervals being provided with radial- 80 ly disposed notches or depressions 20 similar in number to the lugs 17. The flange 19 has an outer depending lip portion 21 and has its rounded top formed with a hollow frusto conical extension 22 in which the end 90 of the nipple 11 is received.

The base 1, between the flanges 2 and 5 thereof, provides an oil pen. Air is admitted through the bottom of the burner through the opening 4 and air is likewise admitted 95 into the hollow member 8 through the spaces between the legs 6 thereof. The oil in the pan is first ignited to heat the fuel conducted through the pipe 16 and to likewise heat the fuel in its passage through the nipple 11. 100 The space between the crown member 18 and the central member 8 serves as a retort and a storage chamber for the vaporized fuel and combustion is initiated adjacent the lip 21 of the flange or ring 19. By providing the outer or crown member 18 with the notches or depressions 20 and the intermediate member 8 with the lugs 17 the space 105 between the confronting or contacting portions of these members is regulated. This 110 enables the chamber between the dome and the intermediate member to be reduced or

enlarged. When these members are close together the burner will generate on less oil than when the members are spaced away from each other, with the result that the intensity and consequently the intensity of the heat from the flame may be thus regulated. The oil conductor pipe 16 and the oil jet nipple 11 are continuously filled which prevents carbonization. The hollow extension 22 on the crown member 18 acts as a receptacle for oil, or for gas from the nipple 11, and any oil which may pass through the jet, before the burner is sufficiently heated to vaporize such oil, will be directed through the conduits 9 over the frusto conical top portion of the member 8 into the pan 25, which, as heretofore stated, is provided by the burner 1 between the flanges 2 and 5.

The simplicity of my improvement and the advantages thereof, will, it is believed, be perfectly apparent to those skilled in the art to which such invention relates, when the foregoing description is carefully read in connection with the accompanying drawings.

Having described the invention, I claim:—

1. A hydro-carbon burner, comprising a base having a central opening therethrough which is surrounded by an upstanding flange and which base has an upstanding outer flange providing an oil pan between said flanges, said base having its under face formed with a continuous depending flange, a dome-shaped member having depending legs arranged in and resting on the pan, a crown member arranged over the central member and having a central hollow frusto conical extension, means between the crown and central member for raising the former on the latter to regulate the space therebetween, an oil jet nipple screwed through the central member and having its end received in the frusto conical extension of the outer member, a T coupling screwed to

the inner end of the nipple, a threaded plug closing the outer passage through the coupling, a cross bar screwed on the plug and contacting the under face of the base and a fuel conducting pipe connected with the lateral branch of the T-coupling.

2. A hydro-carbon burner, including a base having an outer continuous upstanding flange, a central opening surrounded by an upstanding flange and a lower depending flange between the upstanding flanges, said first mentioned flanges providing an oil pan therebetween, a central hollow frusto conical member having an extending flange formed with depending feet which are received in and rest on the pan, said member having radially disposed grooves providing oil conduits directed from the center to the upper face thereof, the upper face of the flange of the said central member being formed with equidistantly spaced upstanding lugs, an oil jet nipple screwed through the top of the said member, a T-coupling in which the nipple is screwed, a threaded plug closing the lower passage through the T-coupling, a cross bar threaded on the plug and contacting the under face of the base, an oil conducting pipe screwed in the lateral branch of the T-coupling, an outer crown member having an inner continuous flange, formed with a beaded edge, said flange having equidistantly spaced notches designed to receive the lugs therein when the crown member is to be arranged close to the central member and the said flange designed to rest directly on the lugs when the crown member is to be spaced away from the intermediate member, and said crown member having a frusto conical extension in which the outer end of the nipple is received.

In testimony whereof I affix my signature.

RUFUS M. STONE.
